(57) CLAIM

The ornamental design for packaging for confectioneries, as shown and described.

DESCRIPTION

FIG. 1 is a perspective view of a first embodiment of a packaging for confectioneries according to the present invention, having a label space, wherein the packaging is in its folded state;

FIG. 2 is a front elevation view of the packaging of FIG. 1; FIG. 3 is a rear elevation view of the packaging of FIG. 1; FIG. 4 is a right side elevation view of the packaging of FIG. 1 wherein the left side elevation view is a mirror image thereof;

FIG. 5 is a top plan view of the packaging of FIG. 1; FIG. 6 is a bottom plan view of the packaging of FIG. 1; FIG. 7 is a perspective view of a second embodiment of packaging for confectioneries according to the present invention like that of FIG. 1, except that no label space is shown, and wherein the front elevation view, rear elevation view, right side elevation view, and bottom plan view are the same as in FIGS. 2, 3, 4, and 6, respectively, and the left side elevation view is a mirror image of the right side elevation view;

FIG. 8 is a top plan view of the packaging of FIG. 7; FIG. 9 is a perspective view of the first embodiment of the packaging for confectionaries according to the present invention in an alternate configuration, wherein the embodiment of FIG. 1 has been unfolded and then refolded into a shirt design, with a label space shown in solid lines; FIG. 10 is a front elevation view of the packaging of FIG. 9;

FIG. 11 is a rear elevation view of the packaging of FIG. 9; FIG. 12 is a right side elevation view of the packaging of FIG. 9 wherein the left side view is a mirror image thereof; FIG. 13 is a top plan view of the packaging of FIG. 9; FIG. 14 is a bottom plan view of the packaging of FIG. 9; and

FIG. 15 is a top plan view of a second embodiment of packaging for confectioneries according to the present invention like that of FIG. 9, except that no label space is shown, wherein the front elevation view, rear elevation view, right side elevation view, and bottom plan view are the same as in FIGS. 10, 11, 12, and 14, respectively, and the left side elevation view is a mirror image of the right side elevation view; and,

FIG. 16 is a top plan view of the packaging of FIG. 15. All portions of the drawings shown in dashed lines depict environmental subject matter only and form no part of the claimed design.
